SPOOL HOLDER

James L. Reynolds, Elizabethton, Tenn., assignor,
by mesne assignments, to Beaunit Mills, Inc.,
New York, N. Y., a corporation of New York

Application August 2, 1949, Serial No. 108,166

4 Claims. (Cl. 242—68)

1

This invention relates to a yarn-packaging system applicable to winding machines of the type wherein the material per se on the spools or other packages undergoing winding engages frictionally with rotating driving elements carried by the machine.

In winding machines of this type, the driving elements comprise rotating drums, rollers, or the like, covered with a friction surface such as rubber, cork, canvas, or the like, against which bear the driven members, which are constituted as spools or rollers on which the thread or yarn is to be wound. The material undergoing winding therefore acts as the power-transmitting medium between the driving and the driven members. After a predetermined quantity thereof has collected on the driven member the latter must be replaced by an empty one, the full member being usually brought out of contact with the driving member manually or through agency of devices responsive to the amount of material that has accumulated on the driven member.

The driven members heretofore employed in surface-driven winding machines of the aforesaid type usually comprise solid roller-like structures provided with laterally extending stud shafts, carried in quickly removable fashion in socket-like bearings on the machine frame. Such rollers must be accurately machined to insure uniform winding and are therefore expensive. When a roller is filled it must be removed and so long as yarn remains thereon, the roller is kept out of use and an empty one of equal quality must be substituted for it.

It is the primary object of the present invention to provide a yarn-packaging system wherein the usual expensive solid rollers are replaced by an allocated minimum number of accurate arbors on which, however, relatively inexpensive but accurate, easily produced, interchangeable sleeves that serve as the actual yarn- or thread-collecting means can be successively mounted. An additional object is to provide means for latching such sleeves in assembled relation on the arbor portion while the winding is taking place but adapted so as to permit immediate removal of a material-laden sleeve from the arbor portion for replacement by an empty sleeve.

Another object of the invention is to provide a smoothly acting, resilient, frictionally-operated latching means for retaining the arbor and sleeve portions in assembled relation during winding operations.

To this end the packaging device of the system is constituted of an arbor portion and a sleeve

2

portion, the latter fitting lengthwise and frictionally over the former, the sleeve being provided near its ends with circumferential internal grooves of substantially hemispherical cross-section into which spring-urged latching members of similar substantially hemispherical shape carried by the arbor portion, engage. An extremely accurate and smooth-acting latching action is thus obtained.

10 The arrangement is illustrated in the drawing, where:

Fig. 1 shows the arbor portion and cooperating sleeve in separated condition.

Fig. 2 is a longitudinal cross section through the arbor and sleeve, the parts being shown in assembled condition.

Fig. 3 is a section through the arbor portion taken along line 3—3 of Fig. 2.

Fig. 4 is an outside end view of the device as assembled.

Referring to the drawing, the yarn packaging arrangement comprises a hollow sleeve portion indicated generally at 1 and an arbor portion over which the sleeve 1 fits. The arbor portion may be a solid cylinder but for economy in manufacture it is preferably constituted of a plurality of readily machined and assembled separate members such as the hollow cylindrical portion 2 and the end members 3 and 4. The latter are held in place in the portion 2 in any suitable manner as by being forced into place, cemented, pinned, or fastened by screws. In the preferred embodiment, and likewise for convenience in manufacture, flanges 5 and 6 are provided on the end members 3 and 4. One of the flanges, for example, 6, however, extends up beyond the surface of portion 2 to serve as a limiting stop and position-defining means for the sleeve portion 1 when the latter is slipped lengthwise over the member 2 of the arbor portion.

40 The sleeve 1 is provided at a short distance from each edge with a circumferential groove 7 of substantially hemispherical cross section. The arbor is provided with a suitable number of peripherally spaced spring-urged friction latching devices. Each device is constituted of a substantially hemispherically shaped head 8 protruding through a retaining yoke 9 under the action of a coil spring 10 bearing against a flange 13 on the bottom of the head member 8 and larger than the aperture in the yoke 9 through which the head 8 passes. The latching devices are preferably constituted as assembled units adapted for mounting in one of the end members, e. g. end member 4, as by drilling circumferen-

tially spaced holes therein as shown in Fig. 3 and frictionally inserting the devices or otherwise securing them therein. When mounted in place, the tops of the substantially hemispherically shaped heads 8 extend above the surface of the cylindrical portion 2 of the arbor portion to an extent that will permit the head 8 to snap smoothly into and substantially fill the correspondingly shaped groove 7 of the sleeve 1 when the latter is longitudinally pushed into place, the inside peripheral edges of sleeve 1 being suitably chamfered to permit easy positioning thereof on the arbor portion.

The arbor portion of the device is provided with means for mounting the same on the winding machine, such as stud shafts 11 screwed into the end members of the arbor portion as at 13 and retained by locknuts 12. A unitary shaft extending entirely through the arbor portion and having laterally extending stud ends may also be used.

The parts of the arbor and sleeve may be made of any suitable material. The sleeve however is preferably made of a suitable readily molded and machinable synthetic resin, of laminated structure if desired. A set of spring-actuated latches may also, if desired, be disposed at each end of the arbor portion, that is, mounted in peripherally spaced relation to each other in end member 4 as well as in end member 3. An internal peripheral groove 7 is preferably provided at each end of the sleeve, thus making it unnecessary for the operator to ascertain which end has the groove that cooperates with the latches.

The operation of the arrangement is as follows:

Only a predetermined allocated number of arbor portions, as shown at the left hand side of Fig. 1 or interiorly of Fig. 2, need be provided for each winding machine. However any desired number of sleeves 1 may be provided for successive interchangeable use on the aforesaid arbors. In use, a sleeve is slipped on to an arbor; the assembled unit is then placed in position on the winding machine so as to cause the sleeve to contact with a frictional driving member of the machine. The yarn, thread or the like that is to be packaged is suitably attached to the surface of the sleeve and allowed to accumulate thereon, the rotation of the sleeve and arbor unit being effected by contact of the accumulated material with the frictional driving member of the machine. When sufficient material has collected on the sleeve, the entire unit is removed from the machine, the full sleeve 1 is slipped off from the arbor portion and replaced by an empty sleeve.

What is claimed is:

1. In a mandrel of the type adapted for carrying interchangeable sleeves intended for winding yarn or the like thereon which are provided with internal circumferential grooves and the mandrel with yieldable latching elements protruding from the surface thereof and engaging in said grooves to hold said sleeves in position, the improvement consisting in constituting said mandrel as a structure comprising two spaced short cylindrical end members each having a radially extending flange at the outer side, a tubular member tightly fitted to said end members, the ends of said tubular member abutting against said flanges, the outer surface of said tubular member serving as the support for the interchangeable sleeves, the flange at the outer side of one of said end members extending above the surface of said

60

tubular member to serve as a stop for positioning the interchangeable sleeves on said mandrel, the flange on the other of said end members terminating flush with the surface of said tubular member to permit insertion of said mandrel into and removal of said mandrel from the interchangeable sleeve, a plurality of spring-pressed latching members protruding peripherally above the surface of said tubular member along a line corresponding to the location of a groove in the interchangeable sleeve, sockets extending through said tubular member and into one of said end members for housing said spring-pressed latching members, the portion of said latching members that protrude above the surface of said tubular member being of substantially hemispherical shape.

2. In the mandrel as recited in claim 1, where-in the spring-pressed latching members comprise 20 elements each having substantially hemispherical shape at the top, each of said elements having a flange at the bottom, each of said sockets comprising a yoke encompassing said latching members, an aperture in said yoke through which the 25 substantially hemispherical portion of the corresponding one of said elements protrude, said flange on each of said elements preventing the complete emergence thereof, a spring within said yoke bearing against the bottom thereof and against the corresponding one of said elements, said yoke being carried in frictionally fitting relation in said sockets extending through said tubular member and into one of said end members.

3. In a mandrel of the type adapted for carrying interchangeable sleeves for winding yarn or the like thereon comprising a round hollow cylinder, a removable round sleeve positioned over said cylinder, said cylinder and said sleeve being substantially coextensive, round end members 40 tightly fitted to the ends of said hollow cylinder, stud shafts threaded into said round end members and projecting from the sides thereof, one of said end members having a plurality of radially disposed holes, said holes extending through the end of said cylinder fitted to said last mentioned end member, said holes being substantially equally spaced around the circumference of said cylinder, a spring positioned in each of said holes, a plurality of substantially hemispherical members, one of said hemispherical members being positioned over the spring in each of said holes, the heads of said hemispherical members projecting above the surface of said cylinder so as to yieldably engage the inner surface of said sleeve at spaced points to retain said sleeve on said cylinder during the winding of yarn on said sleeve.

4. In a mandrel of the type adapted for carrying interchangeable sleeves for winding yarn or the like thereon comprising a round hollow cylinder, a removable round sleeve positioned over said cylinder, said cylinder and said sleeve being substantially coextensive, round end members tightly fitted into the ends of said hollow cylinder, one of said end members having a plurality of radially disposed holes, said holes extending through the end of said cylinder fitted to said last mentioned end member, said holes being substantially equally spaced around the circumference of said cylinder, a socket fitted into each of said holes, a spring positioned in each of said sockets, a plurality of substantially hemispherical members, one of said hemispherical members being positioned over the spring in

each of said sockets, the heads of said hemispherical members projecting above the surface of said cylinder so as to yieldably engage the inner surface of said sleeve at spaced points to retain said sleeve on said cylinder during the winding of yarn on said sleeve.
